UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

RECEIVER.

Application filed January 29, 1923. Serial No. 615,591.

To all whom it may concern:

Be it known that I, EDWARD B. Nowosielski, a citizen of the United States, residing at Bloomfield, in the county of Essex, State of New Jersey, have invented certain new and useful Improvements in Receivers, of which the following is a description, reference being had to the accompanying drawing and to the figures of reference marked 10 thereon.

This invention relates to improvements in receivers such as used for the reception and conversion of electrical impulses into sound waves. The invention is particularly useful 15 for head receivers of the ordinary telephone type or such as are used in the reception of wireless messages.

One of the objects of my invention is to provide a construction in which the terminals 20 for the electromagnet used in the receiver, are mounted on a disc of insulating material. These terminals also being utilized to receive the terminals of the connecting cord.

Another object of my invention is to arrange the insulating disc carrying said cord and electro-magnetic terminals in such a way that it serves to clamp and hold the permanent magnet and electro-magnets in 25 the receiver casing.

Another object of my invention is to provide a simple but effective means for holding the spool heads of the electro-magnets in position on their respective cores.

Other and further objects will be apparent to one skilled in the art after a study of the annexed specification taken in connection with the attached drawing, wherein:

Figure 1 is a plan view of the receiver with the ear cap and diaphragm removed and with a portion of the terminal disc broken away thereby showing only one of the terminals.

Figure 2 is a sectional view through a portion of the disc and the terminals.

Figure 3 is a section on the line 3/3 of Fig. 2.

Referring now to the details wherein like numbers refer to corresponding parts in the various views, 1 is a casing preferably of insulating material within which a magnet 2 is positioned so as to closely follow the contour of the interior wall of the casing. The pole ends of the magnet are preferably bent inward away from the inner wall of the cas-

ing as is clearly indicated. Extending from the pole ends are pole pieces 3 which terminate in core ends. The bottom of the pole pieces 3 rest against the bottom of the casing and these pole pieces, together with the 60 magnet 2, are held in position by screws 5 which pass through the casing and nuts 6 on the inner ends of the screws. The bolts 5 pass through a disc of strong insulating material 7, such as "dielecto," "micarta" or the 65 like, before the application of the nuts 6, so that the disc 7 serves to clamp the magnet and pole piece securely within the receiver shell. A central hole 8 is cut in the disc 7 to receive the spools forming the electromagnet. Each spool has a protecting head 9, preferably of insulating material, which heads are held in place on the core through the medium of snap springs 10 that engage 70 slight notches in the outer ends of the cores 75 4. I prefer this method of securing the spool heads in place over the old methods of stacking the outer end of the cores as is almost universally done for the reason that during the stacking operation some damage 80 may be done to the coil, which consists of very fine wire and such coils will not stand much abuse. The disc 7 carries a pair of connectors 11. These connectors have ears 12 which project through holes in the disc 7 85 and are riveted over on the underside. The connectors 11 have an extended portion 13 to which the outer ends 15 of the electromagnet coils are attached. The cord terminals 16 are adapted to enter an opening 17 formed 90 by bending over a portion 18 of the terminal. A screw 19 serves to force the part 18 tightly against the terminal 16, clamping it in position.

From the drawings and the description 95 above, it will be seen that the disc 17 with the terminals mounted thereon forms a unitary structure which serves to make the connection between the outside conductors and the electromagnet, as well as a clamping 100 means for holding the working parts of the receiver outside of the diaphragm in position.

It will be understood that my invention is susceptible of certain changes in the details 105 without departing from the spirit of the same and the scope of the appended claims.

Having thus described my invention what I claim is:

1. In a device of the class described, a cas- 110

2

ing of insulating material containing a permanent magnet positioned on the bottom of the casing and an electro-magnet having cores engaging the magnet pole ends, a disc 5 of insulated material positioned over the permanent magnet and encompassing the electro-magnet with means passing through said disc and casing only for clamping the permanent and electro-magnets in position 10 and connectors on said disc adapted to receive cord terminals and the ends of the electro-magnet.

2. In a device of the class described, a cas-

ing, a permanent magnet and an electro-magnet, a unitary device for clamping the 15 said magnets in operative position within the casing, said unitary device consisting of a disc of insulating material having connectors preferably riveted thereto, said connectors adapted to receive cord terminals and 20 the outer ends of the electro-magnet and clamping means including a bolt passing through only the casing and disc.

In testimony whereof, I affix my signature.

EDWARD B. NOWOSIELSKI.
